UNITED STATES PATENT OFFICE.

THOMAS C. BARRETT, OF HARTFORD, CONNECTICUT.

STERILIZING DEVICE.

Application filed March 20, 1925, Serial No. 17,056.

To all whom it may concern:

Be it known that I, THOMAS C. BARRETT, a citizen of the United States, residing at Hartford, in the county of Hartford and 5 State of Connecticut, have invented certain new and useful Improvements in Sterilizing Devices, of which the following is a specification.

This invention relates to sterilizing devices, and more particularly to a sterilizer particularly adapted for use in connection with the mouth pieces of telephones.

In the present invention, I provide a casing adapted to receive a disinfectant holder, and further provide a holder arranged above the disinfectant holder and communicating therewith, the upper holder being adapted to removably support a sponge or other absorbing medium shaped to fit the inside of a telephone mouth piece.

An object of the invention is to provide a construction in which the sponge may be readily separated from its supporting member for the purpose of cleaning or replacing the sponge.

A further object is to provide means whereby the disinfectant is always obtainable and at the same time prevent evaporation of it.

30 In the accompanying drawings, I have shown one embodiment of the invention. In this showing:

Figure 1 is a central vertical sectional view,

35 Figure 2 is a horizontal sectional view on line 2-2 of Figure 1,

Figure 3 is a perspective view of a cover or supporting member to which the sponge is attached,

40 Figure 4 is a similar view of a rim used in connection with the supporting member, and,

Figure 5 is a similar view of the sponge.

Referring to the drawings, the reference 45 numeral 1 designates an outer casing which may be made of any desired size and shape and formed of any suitable material. Within the receptacle, I provide a disinfectant holder 2 in the form of a rubber bulb having a neck 3 formed at the top. An upper holder 4 constructed of glass or other suitable material and of approximately the same shape as the telephone mouth piece, is arranged within the casing. This holder is 50 provided with an extension 5 at the bottom, adapted to be received within the neck of

the bulb and provided with a passage 6 through which the disinfectant may flow. A sponge 7 (see Figure 5) is adapted to be arranged within the holder and this sponge 60 is provided with an upper flange 8. A supporting member 9 of suitably rigid material is secured to the flange of the sponge and is provided with a handle 10, by means of which the sponge may be removed from the 65 holder, when desired. As shown, this supporting member is provided with a peripheral flange 11, having spaced projections 12. A rim 13 is adapted to be arranged on the under side of the flange or sponge (see 70 Figure 1) and this rim is provided with cut out portions or recesses 14 similar in shape to the projections 12 and similarly spaced on the rim. The rim is further provided with an upstruck portion 15 to permit 75 it to be rotated to bring the projections 12 and recesses 14 out of alinement (see Figure 2). The outer casing 1 may be provided with a suitable cover 16 which, as shown, may be hinged to the casing.

In operation, the rim 13 is passed over the smaller end of the sponge and arranged beneath the flange. The supporting member 9 is then passed over the top of the sponge and the projections 12 passed over the recesses 14 in the rim. The rim is then turned by engaging the upstruck portion 15 to bring the recesses and projections out of alinement. The sponge is then placed in the holder and when it is to be used, pressure is applied to the handle 10 to depress the upper holder 4 and force the disinfectant through the passage 6 to the sponge. The sponge is then removed and the interior of the mouth piece of the telephone may be 95 cleaned and sterilized by placing the sponge within it and rotating it slightly to apply the disinfectant thereto. The sponge may be readily removed from the supporting member for the purpose of cleaning it or 100 replacing it. The bulb 2 may be refilled with disinfectant by depressing it and pouring the disinfectant through the upper holder. It will be apparent that the supporting member 9 also serves as a cover to prevent the disinfectant from passing upwardly 105 through the sponge and evaporating.

It is to be understood that the form of my invention herewith shown and described is to be taken as a preferred example of the 110 same, and that various changes in the shape, size, and arrangement of parts may be re-

sorted to without departing from the spirit of the invention or the scope of the subjoined claims.

I claim:

- 5 1. In a device of the character described, an outer casing, a compressible bulb arranged in the bottom of said casing and adapted to contain a disinfectant, an upper holder arranged above said bulb and communicating therewith, said upper holder being movable to compress said bulb, and an absorbing member arranged in said upper holder.
- 10 2. In a device of the character described, an outer casing, a compressible bulb arranged in the bottom of said casing and adapted to contain a disinfectant, an upper holder mounted in said casing and communicating with said bulb, said upper holder being movable to compress said bulb and being of substantially the same shape as the mouth piece of a telephone, and a sponge adapted to be received in said upper holder and snugly fit therein.
- 15 3. In a device of the character described, an outer casing, a compressible disinfectant holder arranged in the bottom of said casing, a movable upper holder arranged above said disinfectant holder and communicating therewith, said holder being of substantially the same shape as the mouth piece of a telephone.
- 20 4. In a device of the character described, an outer casing, a disinfectant holder arranged in the bottom of said casing, an upper holder arranged above said disinfectant holder and communicating therewith, said holder being of substantially the same shape as the mouth piece of a telephone, a sponge adapted to be received in said upper holder and snugly fit therein, the upper end of said sponge being provided with a flange, a ring arranged beneath said flange, and a supporting member arranged above said sponge, said supporting member being provided with projections extending beneath said flange and engaging said ring.
- 25 5. In a device of the character described, a compressible disinfectant holder, an upper holder secured to the upper end of said disinfectant holder and communicating therewith, a sponge adapted to be received in said upper holder and snugly fit therein, and a cover arranged over said sponge and adapted to snugly fit the upper edge of said upper holder.

phone, a sponge adapted to be received in said upper holder and snugly fit therein, the upper end of said sponge being provided with a flange, and a supporting member secured to said flange.

4. In a device of the character described, an outer casing, a disinfectant holder arranged in the bottom of said casing, an upper holder arranged above said disinfectant holder and communicating therewith, said holder being of substantially the same shape as the mouth piece of a telephone, a sponge adapted to be received in said upper holder and snugly fit therein, the upper end of said sponge being provided with a flange, a ring arranged beneath said flange, and a supporting member arranged above said sponge, said supporting member being provided with projections extending beneath said flange and engaging said ring.

5. In a device of the character described, a compressible disinfectant holder, an upper holder secured to the upper end of said disinfectant holder and communicating therewith, a sponge adapted to be received in said upper holder and snugly fit therein, and a cover arranged over said sponge and adapted to snugly fit the upper edge of said upper holder.

In testimony whereof, I affix my signature.

THOMAS C. BARRETT.
